FUSE

Daniel E. Carney, Charleroi, Pa., assignor, by direct and mesne assignments, of one-half to James M. Magee and one-half to Harry I. Neaman, both of Pittsburgh, Pa.

Application May 25, 1929, Serial No. 365,929

3 Claims. (Cl. 200—132)

My invention relates to certain new and useful improvements in fuses, more particularly of the knife blade type of fuses commonly employed for protecting electrical circuits from currents 5 which are above their safe carrying capacity.

The electrical industry has long recognized the need and desirability of an efficient fuse of this type, which is refillable, simple in structure, and not open to liability of explosion upon the occurrence of a blow out. Such refillable fuses as have been heretofore developed, contain inherent defects due to multiplicity of holding and sealing washers, necessarily assembled as separate units and thus multiplying the possibilities for presence of dirt and grease in the assembled fuse; the cause of explosions.

The present invention has been designed to overcome and avoid all defects of prior art practice and has as an essential object the provision 20 of a refillable fuse assembled as a two part structure.

Another object is the provision in a fuse of this character of means permanently associated, as by coupling, with an end cap or retaining 25 member, for releasably locking and maintaining the fuse strip assembly against movement relative to the fuse casing.

A further object is the provision in such a fuse, of a detachable end closure and sealing 30 means having self contained blade terminal locking means shiftably associated therewith.

Additional objects of the invention are to provide a fuse of the character described which will greatly facilitate and expedite the renewal of the 35 fuse links embodied therein, which includes a pair of non-bridged terminal blades, which is simple in its construction and arrangement, durable and efficient in its use, positive in its action, and comparatively inexpensive to manufacture, 40 assemble, repair and maintain.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed 45 without departing from the spirit of the invention.

In the drawing wherein like numerals of reference designate corresponding parts throughout the several views:—

55 Figure 1 is a longitudinal cross sectional view

of a knife blade type of fuse constructed in accordance with the invention.

Figure 2 is a bottom end view thereof.

Figure 3 is a side view of my improved fuse.

Figure 4 is an end view of the fuse casing. 5

Figure 5 is a top plan view of the device.

Figure 6 is a top plan view of the locking ring, and Figure 7 is a bottom plan view of the lock washer associated with the latter.

Figure 8 is a side view of the terminal blades 10 joined by the interposed fuse links, with certain of the elements shown in Figure 1 as associated with the blade 7 being omitted.

Referring in detail to the drawing the fuse casing A comprises a hollow cylinder 1 which is 15 open at both ends thereof, and constructed from any suitable insulating material. The top and bottom ends of the cylinder 1 are provided with connecting sleeves, respectively indicated at 2 and 3, which are fixed to the respective ends of 20 the cylinder 1 in any suitable manner.

The connecting sleeves 2 and 3 are provided with exteriorly threaded outer end portions for the engagement of the interiorly threaded clamping caps, respectively indicated at 4 and 5. The 25 outer end of each of the latter is formed with an inwardly disposed annular flange 6'. The outer peripheries of the clamping caps 4 and 5 are knurled to facilitate their manipulation when effecting their engagement with respective connecting sleeves 2 and 3, and their removal from the latter.

A pair of aligned terminal blades, respectively indicated at 6 and 7, are mounted to project from respective ends of the fuse casing A, and 35 are formed with reduced inner end portions 8. A plurality of suitably spaced fuse links 9 are detachably connected to respective end portions 8 within the fuse casing, by means of bolts 10. The fuse links 9 are constructed from some easily 40 fusible metal and of such size that an unsafe, electrical current melts them and breaks the circuit, in the manner well known in the art.

The fuse links 9 are sufficiently rigid to support the terminal blades 6 and 7 in fixed longitudinal 45 alignment relatively to each other, and in consequence, no bridge member, other than the fuse links 9, is required for connecting and supporting the terminal blades 6 and 7.

A cap washer 11, a spacing washer 12 and a 50 lock washer 13, are positioned flatly against each other and are fixedly and permanently connected to the terminal blade 7, in any suitable manner, at the juncture of the latter with its associated reduced portion 8.

The diameter of the spacing washer 12 is somewhat less than the diameters of the cap washer 11 and of the lock washer 13, whereby the combination of the three washers 11, 12 and 13 virtually establishes a peripheral, circumferentially extending groove 14, for the reception of the annular flange 6', of the clamping cap 5.

The outer end of each of the connecting sleeves 2 and 3 is provided with a pair of diametrically opposed flanges 15, which are formed with a pair of diametrically opposed recesses 16. The lock washer 13 carries a pair of fixed, inwardly disposed, and diametrically opposed lugs 17, which extend into and engage in the recesses 16 to prevent the rotation of the associated washers 11, 12 and 13 and of the terminal blade 7 fixed to the latter.

The engagement of the flange 6' in the groove 14 permits of the free rotation of the clamping cap 5 in effecting the attachment of the latter to the sleeve 3, or its release therefrom. In securing the cap 5 to the sleeve 3, the peripheral outer edge of the lock washer 13 is fixedly clamped against the outer edge of the sleeve 3 by the flange 6' of the cap 5, whereby the washers 11, 12 and 13 provide an effective closure element for the bottom end of the fuse casing A, and further serve to rigidly support the terminal blade 7 in the latter.

30 The top of the fuse casing is closed by a lock washer 18 and an associated locking ring 18'. The locking ring 18' is positioned on top of the lock washer 18 and is shiftably connected to the latter by a pair of headed guide pins 19. 35 The guide pins 19 are fixed in the apertures 21 to the lock washer 18 and extend outwardly through a pair of guide slots 20, which are formed in the locking ring 18'.

A pair of diametrically opposed, headed, connecting pins 22 are fixed in apertures 23 to the locking ring 18'. The heads of the connecting pins 22 overlap the outer side of the inner peripheral edge margin of the flange 6', of the clamping cap 4. The engagement of the connecting pins 22 with the flange 6' is such as to permit of the free rotation of the cap 4 on the locking ring 18', while connecting the cap 4 to the latter. The connecting pins 22 further serve as hand-holds for facilitating the adjustment of 50 the ring 18' with respect to the lock washer 18.

The lock washer 18 is formed with an oblong slot 24 for the extension of the terminal blade 6 therethrough. The lock washer 18 is not fixed to the terminal blade 6, but seats against a flash bar 25 which is fixed to the latter at its juncture with the associated reduced portion 8. The purpose of the flash bar 25 is to prevent the potential passage of any flash back through the slot 24 in the event of a blowout of the fuse.

60 The lock washer 18 is provided with a pair of diametrically opposed, inwardly extending lugs 26, which engage in the recesses 16 formed in the flange 15 of the connecting sleeve 2, for preventing the rotation of the lock washer 18 in the latter. The lock washers 18 and 13 are identical in construction and arrangement except that the former is provided with the fixed guide pins 19 and is not fixed to its associated terminal blade 6.

70 The locking ring 18' is formed with a pair of diametrically opposed slots 27 which are open at the inner periphery of the former. The ring slots 27 are provided to allow the passage of the terminal blade 6 through the locking ring 18'.

75 The side edge margins of the terminal blade

6 are also provided with a pair of aligned slots 28, which are oppositely disposed to each other and open at their outer ends. The blade slots 28 are adapted for the reception of the inner peripheral edge margin of the locking ring 18' for rigidly locking the terminal blade 6 to the lock washer 18, as clearly shown in Figure 5.

The peripheral edge margin of the lock washer 18 overlaps the outer end edge of the connecting sleeve 2, and when the cap 4 is secured to the connecting sleeve 2, the lock washer 18 and lock ring 18' are securely clamped between the flange 6' of the cap 4 and the outer end edge of the connecting sleeve 2.

In practice, my improved fuse is taken entirely apart as follows:

The clamping cap 4 is first partially released on the connecting sleeve 2. The locking ring 18' is then shifted on the lock washer 18, a distance permitted by the guide pins 19 in the guide slots 20, which will release the ring from the blade slots 28 and bring the ring slots 27 into proper registration with the blade 6 to allow the latter to be drawn inwardly through the locking ring 18'. The clamping cap 4 is now entirely unscrewed from the sleeve 2, thereby allowing the cap 4, the locking ring 18' and the lock washer 18 to be entirely removed from the blade 6 and from the fuse casing A. The other cap 5 is now unscrewed from the sleeve 3, permitting of the said cap 5, together with the attached washers 11, 12 and 13 and the terminal blades 6 and 7 to be entirely removed from the fuse casing A.

It will here be noted that the lock washer 18 is connected to the locking ring 18' by the guide pins 19, and that the locking ring 18' is in turn connected to the clamping cap 4 by the pins 22. These parts constitute the closure element for the top of the fuse casing and are, 40 of course, removed from and replaced to the latter as a unit.

As the clamping cap 5 is shiftably connected to the washers 11, 12 and 13 and the latter in turn to the terminal blades 6 and 7 and the fuse links 45 9, all of these parts are also removable from and replaceable to the fuse casing A, as a unit.

By this construction and arrangement the top and bottom closure elements for the fuse casing A, may be removed from or replaced to the latter 50 in only two separate units, thereby facilitating and expediting the replacement of the fuse links 9 when required.

In service the fuse is a two-part unit which does not require an entire disassembly in replacing 55 blown fuse elements. Under service conditions a replacement is effected simply by partially releasing the cap 4 and bringing the ring slots 27 into registration with the blade 6 whereupon the cap 5 is unscrewed to remove its assembly from the bottom of the fuse casing. The blade 6 is then allowed to drop inwardly within the fuse casing and by partially rotating the same it may be removed through the lower end of the casing. A new fuse strip structure is then connected between the terminal blade extensions 8 and the entire assembly is reinserted within the casing from right to left as seen in Figure 1 moving the blade 6 through the end cap assembly 4. With the cap 5 screwed home the fuse strip assembly is properly positioned and the cap 4 is then given an advance turn to bring the lock ring 18' into interlocking engagement with the blade 6. It will be noted that under the conditions just described the cap 4 constitutes and remains a part of the 75

casing so that the fuse is in reality a two-part fuse.

The present invention provides a most efficient device of its kind, which may be cheaply manufactured and conveniently maintained.

5 What I claim is:

1. In a fuse, a casing, a fuse strip assembly insertable through the casing and having projecting terminals, a closure for one end thereof, and a unitary locking and closure cap connected to the other end of the casing in assembled or disassembled positions and engageable with the projecting terminal of the strip assembly to prevent axial and rotary movement thereof.

10 2. A two-part renewable fuse including a casing having a combined unitary locking and closure cap on its outer end connected therewith in

assembled or disassembled positions, and a fuse strip assembly with projecting terminals insertable through said casing carrying a permanently attached casing closure cap on the inner end portion of the same, the outer projecting terminal of the strip assembly being engageable by the combined locking and closure cap to prevent axial and rotary movement thereof when assembled.

15 3. A two-part refillable fuse; one part comprising a fuse strip assembly having as a permanent part thereof means for closing a casing end; and the other part comprising a casing having a unitary end closure and fuse strip locking cap on one end, into which said first part is insertable through the opposite end, said cap being detachably secured on the casing.

DANIEL E. CARNEY.
